CLAIM

The ornamental design for a dispensing bottle, as shown and described.

DESCRIPTION

FIG. 1 is a front elevational view of a dispensing bottle showing my new design, the rear elevational view being identical;

FIG. 2 is a right side elevational view thereof;

FIG. 3 is a left side elevational view thereof;

FIG. 4 is a top plan view thereof;

FIG. 5 is a bottom plan view thereof;

FIG. 6 is a perspective view thereof showing a closure in the open position;

FIG. 7 is a fragmentary rear elevational view of the top section thereof showing both closures in the open position; and,

FIG. 8 is a top plan view thereof showing both closures in the open position.

FIG. 4

FIG. 2

FIG. 1
